DESIGN FOR A COMBINED SALT SHAKER, PEPPER SHAKER, AND TRAY THEREFOR

Julius Hommer, Union, N. J.

Application October 8, 1940, Serial No. 95,638

Term of patent 7 years

To all whom it may concern:

Be it known that I, Julius Hommer, a citizen of the United States and residing at Union, in the county of Union and State of New Jersey, have invented a new, original, and ornamental Design for a Combined Salt Shaker, Pepper Shaker, and Tray Therefor, of which the following is a specification, reference being had to the accompanying drawing, forming part thereof, and in which:

Fig. 1 is a side elevational view of a combined salt shaker, pepper shaker, and tray therefor, showing my new design;

Fig. 2 is a top plan view;

Fig. 3 is an end elevational view;

Fig. 4 is a top perspective view of one of the shakers removed from the tray, upon a smaller scale as compared to Figs. 1 to 3; and

Fig. 5 is a top perspective view of the tray for the shakers, with the shakers removed, upon a smaller scale as compared to Figs. 1 to 3.

I claim:

The ornamental design for a combined salt shaker, pepper shaker, and tray therefor, substantially as shown.

JULIUS HOMMER.
